UNITED STATES PATENT OFFICE.

EDITH B. COBB, OF CLEVELAND, OHIO.

ASH-TRAY.

1,212,185.

Specification of Letters Patent. Patented Jan. 16, 1917.

Application filed November 22, 1915. Serial No. 62,757.

To all whom it may concern:

Be it known that I, EDITH B. COBB, a citizen of the United States, residing at Cleveland, in the county of Cuyahoga and State of Ohio, have invented certain new and useful Improvements in Ash-Trays, of which the following is a specification.

This invention relates to ash trays for the use of smokers, and has for its principal object to provide a tray which may be conveniently attached to the rim of a plate or other dish to receive cigar ashes while one enjoys his after dinner smoke. With this means at hand, a smoker will not place his cigar ashes upon the plate.

Another object of the invention is to provide simple means for attaching the tray to rims of dishes of various inclinations, which means will permit the adjustment of the tray to a horizontal position and hold the same against tilting.

A further object of this invention is to design the attaching means so that it may serve as a foot for the tray, when it is desired to simply stand the tray upon the table.

In order that the invention may be clearly understood, the same will be hereinafter fully described with reference to the accompanying drawings, which illustrate one form 30 of the device, and the novel features thereof will be distinctly pointed out in the appended claims.

In the drawings like characters of reference indicate corresponding parts.

Figure 1 is a side elevation of an ash tray constructed in accordance with my invention and applied to the rim of a plate, Fig. 2 is a perspective view of the attaching spring, Fig. 3 is a cross sectional view, taken on line 40 3—3 of Fig. 2, and Fig. 4 is an enlarged view of the attaching spring, illustrating it as a foot and showing how the tray is held thereon in a set position.

Referring to the drawings, 1 represents 45 a plate or other dish having a rim 2 from which is supported the ash tray. A suitable spring formed from flat material is employed to attach the ash tray to the rim of the dish. This spring consists of a straight 50 lower or under side 3, which is bent over at 4 and curved on the arc of a circle as shown at 5, and then extends parallel with said under side at 6 to springingly engage the rim of the dish. The free end of the upper 55 side of the spring is slightly curved upwardly at 7 and the lower side thereof be-

eled at 8, for more easy attachment of the spring to the rim of the dish.

The ash tray may be of any desired design. As shown, it comprises a bowl 9 having a cigar holding extension 10.

An important feature of this invention is that the ash tray may be slidably adjusted upon the arc of the attaching spring so that it may have a fixed horizontal position irrespective of the angle at which the spring stands. This is accomplished by securing a headed pin 11 to the bottom of the bowl of the ash tray, which pin passes through a longitudinal slot 12 in said arc 5 of the 70 above described attaching spring. The head of the pin 11 snugly engages the underside of the arc of the spring, and because of this and also on account of the resiliency of said arc, the ash tray will be frictionally held in 75 a desired set position.

Instead of employing the pin 11, the same results may be obtained by fixing to the bottom of the bowl of the ash tray, a strap 13 forming a rectangular eye, through which 80 said arc 5 of the attaching spring passes. The edges 14 of the eye strap 13 engage the under side of the arc 5 of the spring while the bottom of the bowl of the ash tray engages the top side thereof. This permits 85 sliding adjustment of the ash tray upon the arc of the spring, but the action of the spring will retain it in a set position. The ash tray may be moved to and held in a horizontal position when the attaching spring is 90 fixed to the rim of a plate as illustrated in Fig. 1, or when it serves the purpose of a foot for standing upon a table as in Fig. 4.

It will be understood that slight changes in the details of construction may be made 95 without departing from the principle of the invention as defined by the claims.

Having fully described my invention, what I claim is:

1. An ash tray comprising a bowl, a spring for attachment to a support, the spring having a curved portion forming an arc, and the bowl being provided with means for engaging said arc whereby the bowl may be slidably mounted but will be held in a set position by friction exerted by the springy action of the arc, substantially as described.
2. An ash tray comprising a bowl, a spring formed of flat material, the spring consisting of a straight lower side, the lower side 110 being bent over and forming an arc then extending parallel with said lower side, and

means carried by said bowl for engaging said arc of said spring, whereby it is slidably adjustable thereon but will be retained in a set position, substantially as described.

3. An ash tray comprising a bowl, a spring for attachment to a support, the spring having a curved portion, the curved portion of the spring being provided with a

slot, a pin projecting from said bowl and adapted to slide in said slot of the spring, 10 and the pin having a head for engaging the curved portion of the spring to hold said bowl in a set position, substantially as described.

In testimony whereof I affix my signature. 15
EDITH B. COBB.
